(57) **CLAIM**

The ornamental design for an integrated circuit, as shown and described.

DESCRIPTION

FIG. 1 is perspective view, taken from a front, lower-right elevation of a sensing and dispensing integrated circuit;

FIG. 2 is a front plan view of the sensing and dispensing integrated circuit shown in FIG. 1;

FIG. 3 is a back plan view of the sensing and dispensing integrated circuit shown in FIG. 1;

FIG. 4 is a right side plan view of the sensing and dispensing integrated circuit shown in FIG. 1;

FIG. 5 is a left side plan view of the sensing and dispensing integrated circuit shown in FIG. 1;

FIG. 6 is a top plan view of the sensing and dispensing integrated circuit shown in FIG. 1; and,

FIG. 7 is a bottom plan view of the sensing and dispensing integrated circuit shown in FIG. 1.

Broken lines shown in the drawings represent portions of the integrated flex circuit that form no part of the claimed design.
